UNITED STATES PATENT OFFICE.

JACOB R. HESSLER, OF CHICAGO, ILLINOIS.

COMBINED ORGAN AND SEWING-MACHINE.

SPECIFICATION forming part of Letters Patent No. 338,740, dated March 30, 1886.

Application filed July 24, 1885. Serial No. 172,504. (No model.)

To all whom it may concern:

Be it known that I, JACOB R. HESSLER, a citizen of the United States, residing at Chicago, in the county of Cook and State of Illinois, have invented certain new and useful Improvements in a Combined Organ and Sewing-Machine, which are fully set forth in the following specification, reference being had to the accompanying drawings, forming a part hereof, and in which—

Figure 1 is a front view of the organ. Fig. 2 is a front view of the sewing-machine. Fig. 3 is a transverse sectional view on the plane $y y$. Fig. 4 is a transverse sectional view on the plane $x x$ of Figs. 1 and 2.

Like letters of reference denote like parts.

The object of my invention is to combine under one table or case both a sewing-machine and organ, and have an organ and a sewing-machine within the area usually required for the latter, with its usual drawers and a music case and rack with the former. To attain this end, I construct the sewing-machine table k of about the usual area, with a part, d , hinged to the back edge of the machine-table, to form the cover or lid to the keys of the organ, which are here shown, together with the entire action, at C. That part of the wind-producing mechanism a , usually called the "vacuum," extends along the entire length of the organ in its upper part, but is divided into two parts in its lower part by a space or gap, h , in which the treadles f operate. The sides and top of the space h are cut out of the vacuum, are closed with leather or like flexible material, m , such as is used for like purposes in such places. On each side of the space h is an exhaust, b , attached on its inner edge to one of the treadles f by means of a link, g .

The position of the operating parts of the exhaust, vacuum, and treadles are indicated in two positions in dotted outlines in Fig. 3. A spring, l , throws the vacuum into the position shown in full outline.

A music-rack, i , is attached to the lid d , and it is held in its proper position for holding the music by the removable case E , forming the covering of the machine n . Said case is

provided with pockets e , for holding the music, on one or both of its longitudinal sides, and is provided with doors o , hinged to the case E at its bottom.

The shaft p has a free end, p' , upon which the wheel q may be adjusted longitudinally to the pulley of the machine n , thus adapting this part of the construction to any machine n that it may be desired to place upon the table k , which table is constructed so as to receive and hold any form of machine n .

A longitudinal partition, r , extending the entire length and height of the case A , separates the lower part of the machine into two independent apartments, which keep the air mechanism secure from harm and also stiffen the entire case.

What I claim is—

1. A sewing-machine and organ combined, wherein the table k of the case A forms the table of the sewing-machine and cover d of the organ, substantially as specified.

2. In an organ-action, the vacuum a , provided with space h , covered with flexible material m , in combination with the treadles f , substantially as specified.

3. The table k , provided with machine n and lid d , in combination with the organ-action C and the mechanism to operate said action, substantially as specified.

4. The table k , provided with machine n , case E , having pockets e , and lid d , in combination with the organ-action C and the mechanism to operate said action, substantially as specified.

5. The case A , provided with wheel q , adjustable longitudinally on its shaft, action C, and level table k , having lid d , in combination with removable machine n , substantially as specified.

6. In an organ-bellows, the vacuum a , provided with a gap, h , in combination with the treadles f and link g , substantially as specified.

JACOB R. HESSLER.

Witnesses:

Wm. ZIMMERMAN,
A. H. RINTELMAN.
